UNITED STATES PATENT OFFICE.

JOSEPH GILBERT McDONOUGH, OF EAU CLAIRE, WISCONSIN.

LUMBER-GRADING MACHINE.

Application filed July 31, 1916, Serial No. 112,417. Renewed June 26, 1922. Serial No. 570,934.

To all whom it may concern:

Be it known that I, JOSEPH G. McDONOUGH, a citizen of the United States, resident of Eau Claire, county of Eau Claire, State of Wisconsin, have invented certain new and useful Improvements in Lumber-Grading Machines, of which the following is a specification.

In handling dressed lumber or timber, it is frequently desirable to trim it or cut out pieces that are checked or otherwise defective and re-grade the remainder or the part cut out.

The object, therefore, of my invention is to provide a machine by means of which an attendant can grade lumber or timber of different quality as it is trimmed or cross cut, or before or after.

A further object is to provide a machine by means of which a trade-mark as well as a grade character or mark can be applied to the pieces of lumber or timber.

The invention consists generally in various constructions and combinations, all as hereinafter described and particularly pointed out in the claims.

In the accompanying drawings forming part of this specification,

Figure 1 is a vertical sectional view through a grading machine embodying my invention,

Figure 2 is a transverse vertical sectional view of the same,

Figure 3 is a horizontal sectional view, showing a plan of the grading wheel and the operating mechanism,

Figure 4 is a detail view of the mechanism for operating the grading wheel,

Figure 5 is a view corresponding to Figure 4, looking at the opposite side of the wheel,

Figure 6 is a detail sectional view of the push bars for engaging the grading wheel,

Figure 7 is a front view, partially in section, of the grading wheel operating bars,

Figure 8 is a detail view showing the engagement of the grading wheels with the inking roll,

Figures 9, 10 and 11 are detail views showing the application of the grade-marks or characters to the end surface of a piece of lumber,

In the drawing, 2 represents the frame of the machine and 3 is the trimming saw mounted above said frame. 4 is a lumber

platform, provided on said frame, and 6 is a table hinged at 8 in said platform and having a limited vertical movement. This table is counterbalanced preferably by 60 means of a lever 9, centrally mounted in said frame and having a counter-balance weight 10 at one end and connected by a link 11 at its opposite end with the middle portion of said table. There are two of 65 these tables and their abutting ends are spaced apart, as indicated in Figure 1, to allow the saw 3 to operate between them, the saw being swung by suitable mechanism usually provided in machines of this kind 70 and which I do not consider necessary to describe or illustrate.

12 is a rod, mounted to slide in bearings 13 on said frame and having a collar 14 for engaging the underside of the table 6 and 75 raising it out of alignment with the table 6^a. An arm 12' is mounted on the upper end of the rod and overhangs the table for engaging and clamping the lumber during the operation of applying the grading mark 80 thereto. A walking beam 15 is centrally pivoted at 16 and has a pin and slot connection 17 at one end with the rod 12 and at its other end has a similar connection with a second rod 12^a, the parts of the machine being duplicated, one grading device 85 being lowered as the other is raised, and the corresponding parts of the machine I will designate by the same reference numerals with the addition of the exponent 90 "a". A treadle 18 is pivoted at 19 to the frame and has a link connection 20 with the rod 12, the upward movement of this rod to the position shown in Figures 1 and 2 being effected by the downward movement 95 of the rod 12^a and the corresponding depression of the lever 18^a. When this rod is lifted, a corresponding movement will be imparted to the table above it through the engagement of the collar 14 therewith and 100 space will be provided for the upward tilting movement of the grading wheel and its transverse movement across the face of the lumber.

A shaft 19' is mounted transversely of 105 the machine and is provided with a carriage 20'. A hub 21 is journaled in said carriage and a shaft 22 is mounted to slide vertically in said hub and carries upper and lower grading surfaces 24 and 25. Upon 110 these surfaces the trade-mark of the concern operating the machine may be shown

and also the different grade marks or characters used for indicating the different quality of lumber.

I provide a grading wheel in connection with each table, each having an operating mechanism and one wheel positioned to be raised to its marking position when the other one is lowered to its inoperative position beneath its table. I will designate 10 these wheels and the connections therefor by the same reference numerals with the addition of the exponent "a", a description of one being sufficient for both.

The carriage 20' is free to rock with its 15 supporting shaft from a horizontal to an upright position for the purpose of raising the grading wheel from a horizontal to a vertical axis. The carriage 20' is also free to slide with the shaft 19' to carry the wheel back and forth across the end face of the lumber to be marked. The grading wheel is provided with centering pins 26 positioned to contact with a flange 27 which operates to revolve the wheel and adjust it so that the branding marks or characters will be properly positioned to contact with the end surface of the lumber as the wheel is moved across it. Branding rolls 28 are mounted to contact with the grading wheel 30 and with rolls 29 and 30, the latter having ink delivered thereto through a pipe 31 from a pump 32 that is connected with the walking beam 15 through a link 33.

The roll 28 has a ratchet 34 and carries a 35 sheave 35 over which a cable 36 having a counter-shaft balance-weight 37 passes to the treadle lever 18. This roll will be revolved to have ink applied to the surface thereof when the lever 18 is depressed and 40 when the carriage 20' is moved the grading wheel will contact with the inking roll and be thoroughly inked preparatory to tilting it upward to a vertical axis and applying the ink to the end surface of the lumber. 45 One surface of the grading wheel is preferably provided with the trade-mark of the concern using the machine and grading figures, while the other surface has a similar trade-mark thereon and grading letters (see 50 Figures 9, 10 and 11) said wheel being capable of adjustment vertically to bring either surface into marking position, and I will now proceed to describe the mechanism which I prefer to employ for performing 55 this adjustment.

Referring to Sheet 2 of the drawings, 38 represents a lever pivoted at 39 and having a fork connection at 40 with the hub of the grading wheels. 41 is a slide having a slot 60 42 and a pin 43 passes through said slot, with its ends mounted in the walls of a guide 44. Downward movement of the slide 41 will depress one end of the lever 38 and raise the other end to lift the lower grading 65 surface of the wheel into position to brand

the end surface of the lumber, and when the slide 41 is released, the weight of the grading wheel will tilt the lever 38 downwardly and bring the upper grading surface opposite the surface of the lumber.

As previously stated, the grading wheel is revolved by contact of its pins 26 with the flange 27 and for the purpose of adjusting the proper grading numeral or character in position to contact with the lumber I provide a series of lugs 45 in the hub of the grading wheel in staggered relation to one another and in position to contact with the bars 46, 47, 48 and 49, which are mounted in the carriage 20 in position to be operated by the levers 50, 51, 52 and 53, said levers being mounted on the pin 43 and having a rocking movement thereon to operate their bars respectively and project them into the path of a lug on the hub of the grading wheel. These bars have projections 54 thereon engaged by springs 55 which normally hold the bars in a retracted position or out of the path of the lugs on the grading wheel. The upper grading surface I prefer to equip with the grading numerals 1, 2, 3, and 4, and the lower surface with the letters A, B, C and D, and by the operation of the lever 38 and the series of levers 50 to 53 any desired grade number or character can be applied to the end surface of the lumber and applied in such a way through the printing surfaces of the wheels that a permanent grade mark will appear and the planing mill turning out the lumber can be easily determined by retail dealers or builders.

This marking or grading mechanism can be readily adapted for marking or impressing other surfaces of the lumber or timber, as well as the ends.

When the treadle 18^a is depressed, the sheave 35^a will revolve the shaft upon which the inking rollers 28 and 28^a are mounted and the roller 28 will be revolved toward the right in Figure 2. The marking discs 24 and 25 being in contact with the roller, will revolve also, the pins 26 being out of contact with the guide bar 27 when in this position. Ink will then be applied to all the characters upon the disc. Upon grasping the handle 44 and depressing the lever 53, as shown in Figure 5, the bar 49 will be pushed into the path of the lug 45 on the hub 21 (see Figure 6) and stop the discs from revolving. If the characters on the discs are out of alignment when movement is thus checked, one of the pins 26 will come in contact with the end of the guide bar 27. As the lever 44 is pushed forward while still in its horizontal position, the pin will contact with the guide bar 27 and revolve the discs sufficiently to return the lug 45 into contact with the bar 49. The lever is then raised to its vertical position (see Figures 3,

4 and 7) and as it is being pushed forward the discs will come in contact with the end of the board, the motion of the disc being reversed and it being free to revolve as the 5 lug 45 leaves the bar 49 (see Figure 6).

As shown in Figure 5, the slide 41 is not depressed after the pins 26 come in contact with the bar 27 and while the lever 44 is being raised. It will also be noted that the 10 slide 41 cannot be pressed down until after the lever 53 is moved and the discs are being raised to the vertical position for the reason that the discs, as shown in Figure 8, would strike the guide bar 27 and could not 15 be pushed outward. The grading surface 26 coming in contact with the board when the disc is raised will revolve and impress thereon the desired character.

I claim as my invention:

20 1. A grading wheel comprising upper and lower peripheral grading surfaces having marks or characters thereon, means for raising and lowering said wheel to bring its grading surfaces into alignment with the 25 surface of the lumber to be marked, said wheel having a movement across the face of the lumber and also revolving on a vertical axis and means for supporting lumber adjacent to said wheel.

30 2. A grading wheel having a surface provided with peripheral grading marks, said wheel being mounted for vertical and rotary movement, a lever device for raising said wheel to adjust its peripheral grading marks 35 opposite the face of the lumber, a series of bars corresponding in number to the different grading characters and numbers and positioned to adjust a certain designated mark or number opposite the face of the 40 lumber, and levers for operating said bars to adjust them respectively in the path of said grading wheel, said wheel having means opposite the marks respectively for engaging said bars and means for supporting lumber adjacent to said wheel.

45 3. A grading wheel having a plurality of grading faces provided with marks or characters thereon and mounted to revolve against the face of the lumber to be marked, and means for causing said wheel in its 50 rotary movement to adjust a predetermined mark or character in position to contact with the lumber and means for supporting lumber adjacent to said wheel.

55 4. The combination, with a frame, of tilting lumber tables mounted therein and having abutting ends, means for raising either one of said tables to provide an unobstructed space opposite the end of the lumber 60 on the other table, lumber grading wheels mounted to move into the space beneath the raised table in position to contact with the end surface of the lumber on the other table, said wheels having a plurality of grading surfaces and mounted for

rotary and vertical movement on their axes, and means for raising and lowering said wheels to adjust said grading surfaces in the plane of the lumber to be marked.

5. The combination, with a frame having 70 a table adapted to support lumber thereon, of a grading wheel having a plurality of peripheral grading surfaces, a carriage mounted for movement transversely of the lumber table and wherein said wheel 75 is journaled for rotary and axial movement, said carriage being mounted to tilt and adjust said wheel in a position opposite the surface of the lumber to be marked, and means for raising and 80 lowering said wheel to adjust said grading surfaces in alignment to the surface of the lumber.

6. The combination, with means for separating the severed ends of pieces of lumber or timber, of a grading device mounted 85 to make a mark or impression on the severed end and means for positioning the proper grading mark opposite the surface to be impressed.

7. The combination, with means for separating the severed ends of pieces of lumber or timber, of a grading device provided 90 with groups of grading marks and means for adjusting said grading device to present the proper mark opposite the surface to be impressed.

8. The combination, with means for separating the severed abutting ends of pieces of lumber or timber, of a grading wheel 100 having peripheral marks or characters thereon, mechanism for elevating said wheel to its marking position, and selective means for adjusting the desired mark opposite the surface to be impressed.

9. The combination, with means for separating the severed ends of pieces of lumber or timber, of grading wheels having groups of peripheral marks or characters thereon mounted for adjustment opposite 110 the end surfaces of such pieces of lumber or timber, and selective means for adjusting said wheels rotatively to present the desired marking character opposite the surface to be impressed.

10. The combination, with lumber or timber supporting means, of a grading device mounted for adjustment opposite the end surface of the timber, and selective means for regulating the rotary adjustment of said 120 grading device to present the desired mark or character opposite the surface to be impressed.

11. The combination, with a lumber or timber supporting means and a clamp for 125 holding the lumber, of a grading device mounted for axial and rotary movement and mechanism for effecting such movement to present a selected mark opposite the surface to be impressed,

12. The combination, with a lumber or timber supporting means, of a grading device mounted for movement back and forth over a surface of the lumber to be marked, and means for selectively positioning a grading mark in said grading device opposite such surface. 65
13. The combination, with means for separating the severed abutting ends of pieces of lumber or timber, of a grading device mounted for applying a grading mark or character to the faces of pieces of lumber of varying thickness, and selective means for positioning said device to present the desired mark or character to the surface to be impressed. 70
14. The combination, with means for separating abutting pieces of lumber or timber, of means for applying a trade-mark and a grade-mark to an exposed end surface of any or all of said pieces of lumber or timber. 75
15. The combination, with a lumber supporting table having means for holding a piece of lumber or timber thereon with a transversely severed end surface, of a grading device mounted for movement back and forth on said surface for applying a grade mark thereto. 80
16. In combination, with lumber or timber supporting means adapted to hold pieces of lumber one above the other, a vertically adjustable grading device, and means for operation by an attendant for selectively adjusting a grading name on said device and moving it into contact with the lumber or timber. 85
17. In combination, with lumber or timber supporting means adapted to support pieces of lumber one above the other, a vertically adjustable grading device, and means for operation by an attendant for selectively positioning a grading name and engaging a surface of the lumber or timber with said grading name. 90
18. In combination, with lumber or timber supporting means, a grading device, means for operation by an attendant for selectively adjusting a grading mark on said device on a horizontal and vertical axis for contact with the surface of the lumber or timber. 95
19. In combination with lumber or timber supporting means adapted for surface inspection of lumber of different length, thickness and grades, a grading device, and means for operation by an attendant for selectively adjusting a grading name on said device to apply the proper grade mark to pieces of different length and thickness and contacting said device with such pieces. 100
20. In combination with lumber or timber supporting means, a grading device adjustable vertically on a horizontal axis and having a plurality of grade names therefor for selective contact with the lumber, and mechanism for positioning said grade names for contact with the lumber. 105
21. In combination, with lumber or timber supporting means, a grading device adjustable vertically and on a horizontal axis, and means for operation by an attendant to selectively engage said device and the lumber or timber. 110
22. The combination, with lumber or timber supporting means adopted for inspection and determination of the grade of lumber, of a grading device mounted for adjustment opposite surfaces of the lumber of different thickness and length and selective means for regulating the rotary adjustment of said grading device to present the desired mark opposite the surface to be marked. 115
23. The combination with means separating pieces of lumber of different grades but of the same dimensions so that the grade of each piece may be separately determined, of means for applying the proper grade mark to each of the pieces of lumber of different grade. 120
24. The combination with means separating pieces of lumber differing in grade and in quality and in size, of a grade marking device applying the proper grade mark to the pieces of different grade, quality and size. 125
25. In combination with means for supporting pieces of lumber or timber one above the other, of a grading device mounted for vertical movement to a grade marking position opposite the surface of the lumber or timber to be marked, and means for selectively adjusting said grading device to present the proper grading mark in position for contact with the surface of the lumber or timber. 130
26. In combination with means for supporting pieces of lumber or timber one above the other, of a grading device mounted for vertical movement to a grade marking position opposite the surface of the lumber or timber to be marked, and means for selectively adjusting said grading device to present the proper grading mark in position for contact with the surface of the lumber or timber. 135
27. In combination with means for supporting pieces of lumber or timber, of a grading device below the plane of the lumber and mounted for vertical movement to a grade-marking position adjacent the surface of the lumber or timber to be marked, and means within control of the operator for selectively adjusting said grading device to present the proper grading mark in position for contact with the surface of the lumber or timber. 140
- In witness whereof, I have hereunto set my hand this 20 day of July, 1916.
JOSEPH GILBERT McDONOUGH. 145
